(57) **CLAIM**

The ornamental design for a display screen or portion thereof with graphical user interface, substantially as shown and described.

DESCRIPTION

The sole FIGURE is a front view of a display screen or portion thereof with graphical user interface showing my new design.

The outermost broken lines show a display screen or portion thereof and form no part of the claimed design. The remaining broken lines, showing the word "KodeKey", illustrate a portion of the graphical user interface, and form no part of the claimed design.

1 Claim, 1 Drawing Sheet
